UNITED STATES PATENT OFFICE

2,416,167

YARN CARRIER

Ernest A. Feustel, Hasbrouck Heights, N. J., assignor to Ernest A. Feustel, Inc., East Rutherford, N. J., a corporation of New Jersey

Application March 18, 1944, Serial No. 527,089

8 Claims. (Cl. 66—126)

1

The present invention relates to certain new and useful improvements in the guiding of yarns to needles, spools, cones and the like and it relates to the guiding of such thread along paths other than a straight line and it relates more particularly to yarn-carriers for full-fashioned hosiery knitting machines or for other knitting machines or the like, wherein relatively fine and delicate threads or filaments must be paid out at relatively high linear speeds, and wherein a plurality of yarn-carriers must work in small spaces with relatively small clearances.

An object of the present invention is to provide a more efficient yarn carrier and one which will guide the thread with a minimum of friction and wear. Another object of the present invention is to provide a yarn carrier having more efficient replaceable yarn-guiding means at the upper end or base thereof, and to provide more effective "apron" plate and other devices or parts to be associated with yarn-carriers.

Other objects and advantages of the present invention are apparent in the following detailed description, appended claims and accompanying drawings.

In full-fashioned hosiery knitting machines, it has been the practice to provide yarn carriers or yarn-guiding fingers with small, fine-bore tubes at the delivery ends thereof through which the thread passes and is paid out across the needle bank in front of the sinkers, as shown, for example, in my Patent No. 2,126,249, issued August 9, 1938.

In constructions heretofore employed, it has been conventional to provide eyes at the upper end of the yarn carrier to guide the thread before it reaches the tube at the delivery or pay-out end of the carrier.

These conventional constructions, however, have not been entirely satisfactory since they cause fraying and undue wear of the thread and since wearing out of conventional upper-yarn guiding eyes or the like has entailed either considerable repair work or, indeed, replacement of the entire yarn carrier.

Accordingly, the present invention contemplates the provision of certain new and improved yarn-guiding means at the upper end of the yarn carrier which will more efficiently guide the yarn or thread along the angled path required and which will permit the yarn-guiding means to be quickly and easily replaced when such replacement is required due to wear or other factors.

More specifically, the present invention contemplates means whereby one or more yarn guide

2

tubes can be detachably mounted at the upper end of the yarn carrier so as more efficiently to guide the thread or yarn passing therewith to the pay-out tube at the delivery end of the yarn carrier.

For the purpose of illustrating the invention, there are shown in the accompanying drawings forms thereof which are at present preferred, since the same have been found in practice to give satisfactory and reliable results, although it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

20 Figure 1 represents a perspective view, on a somewhat enlarged scale, of one embodiment of the present invention.

Figure 2 represents a fragmentary perspective view generally similar to that of Figure 1 but 25 showing another embodiment of the present invention.

Figure 3 represents a fragmentary perspective view generally similar to that of Figure 2 but showing still another embodiment of the present 30 invention.

Figure 4 represents a cross-sectional view, on a further enlarged scale, generally along the line 4—4 of Figure 1.

Figure 5 represents a cross-sectional view on a 35 further enlarged scale generally along the line 5—5 of Figure 3.

Figure 6 represents a cross-sectional view generally similar to that of Figure 4 but showing a preliminary stage in the formation of the structure.

Figure 7 represents a cross-sectional view generally similar to that of Figure 6 but showing the appearance of the parts in an intermediate stage of construction.

45 Figure 8 represents a cross-sectional view generally similar to that of Figures 6 and 7 but showing the appearance of the parts after the construction has been completed but before the yarn-guide tube of Figure 4 has been inserted.

Figure 9 represents a cross-sectional view, on a further enlarged scale, generally along the line 9—9 of Figure 1.

Figure 10 represents a cross-sectional view, on an enlarged scale, generally along the line 10—10 50 of Figure 1.

3

Figure 11 represents a cross-sectional view, on an enlarged scale, generally along the line 11-11 of Figure 2.

Figure 12 represents a fragmentary view, on an enlarged scale, partly in elevation and partly in cross-section of a modified form of yarn guide tube which may be used in place of the rear tube 39 of Figure 1.

In one embodiment of the present invention shown generally in Figures 1, 4, 9 and 10. I may provide a yarn carrier base plate 20 of metal or other suitable material to which an elongated yarn guide finger 21 of metal or other suitable material is adjustably connected.

The base plate 20 is removably mounted upon a supporting bar 22 by a pair of screw-threaded bolts 23.

The base plate 20 is provided with a transversely-extending fold-zone 24 so that the forward portion 25 thereof is inclined slightly upwardly relative to the rearward portion 26 thereof.

The forward end of the base plate 20 is provided with a pair of generally parallel longitudinally-extending slots 27.

A transversely-extending yoke-plate 28 of metal or other suitable material is disposed on top of the slotted forward end of said base plate 20 and is provided with a pair of openings 29 which are in registration with the slots 27.

The yarn guide finger 21 has an integrally-formed transversely-enlarged rear end 30 which is adapted to be positioned underneath the slotted forward end of said base plate 20. The rear end 30 of the finger 21 is provided with a pair of screw-threaded openings 31 which are in registration with the slots 27 and the openings 29.

A pair of screw-threaded bolts 32 are adapted to pass through the openings 29 and the slots 27 and to engage within the screw-threaded openings 31 thereby to connect the finger 21 to the base plate 20.

It is apparent that, by loosening the bolts 32, the yoke plate 28 and the rear end 30 can be moved longitudinally relative to the base plate 20 (the bolts 32 moving within the slots 27) so as to permit longitudinal adjustment of the finger 21.

The finger 21 is bent generally along the zone 33 somewhat above the pay-out end thereof and is slotted to provide a central grooved tongue 34 and a pair of gripping jaws 35 which are adapted to grip a downwardly-tapered yarn guide delivery tube 36 as shown in my Patent No. 2,289,256, issued July 7, 1942.

In order more efficiently to guide the thread or yarn 37 along the inclined portions 25 and 26 of the base plate 20, I may provide yarn guide tubes 38 and 39 which extend longitudinally along said portions 25 and 26 respectively.

The rearmost yarn guide tube 39 is adapted removably to be mounted upon the portion 26 of said base plate 20 adjacent the upper face thereof by means of transversely-extending bridging portions which are struck out of the base plate 20 as will be hereinafter described.

In forming the tube-holding bridging portions, a plurality (for example 5) of transverse slits 40 are provided in the tapered rear end 41 of the portion 26. As shown in Figure 6, alternate strips of metal formed by the slits 40 are then forced outwardly in opposite directions. That is, strips 42 are forced downwardly beyond the under surface of the portion 26 while alternate strips 43 are forced upwardly beyond the upper surface of the portion 26.

Generally semi-circular grooves 44 are then

4

formed on the bottoms of the downwardly-pressed strips 42 by any suitable milling operation while similar semi-circular grooves 45 are formed on the tops of the upwardly-pressed strips 43, as shown in Figure 7. It is apparent that all of the grooves 44 can be formed in a single operation and that all the grooves 45 can be formed in a single operation.

After the grooves 44 and 45 have been formed, the strips 43 are pressed downwardly to more or less their original plane position, while the strips 42 are pressed upwardly beyond the upper surface of the portion 26, as shown in Figure 8. In this final position, the grooves 44 and 45 face each other as shown in Figure 8 and are adapted removably to receive the tubular yarn guide tube 39 which has an outside curvature corresponding generally to the cross-section of the grooves 44 and 45.

Similar grooved strips 42 and 43 are formed at the forward end of the portion 26 of the base plate 20 generally adjacent the fold-zone 24 of said base plate.

An elongated longitudinal opening 46 is formed in the portion 26 between the front and rear groups of bridging strips 42 and 43.

The yarn guide tube 39 is positioned intermediate the strips 42 and 43 by inserting it therebetween from the rear end of the base plate 20.

As can be seen particularly in Figures 1 and 9, the yarn guide tube 39 extends from somewhat beyond the rear end of the base plate 20 to generally the fold-zone 24 thereof.

An elongated longitudinal opening 47 is formed along the forward portion 25 of the base plate 20 and extends generally from the fold-zone 24 to a point short of the forward edge of said portion 25; the opening 47 extending intermediate the slots 27 of said portion 25.

Upper and lower grooved bridging strips 48 and 49 respectively are formed on the yoke-plate 28; the strips 48 and 49 being similar to the strips 42 and 43.

As shown particularly in Figures 1 and 10, the grooved bridging strips 48 and 49 are adapted removably to hold the yarn-guide tube 38 in generally the same manner as described hereinabove in connection with the yarn-guide tube 39.

As can be seen particularly in Figures 1 and 9, the yarn or thread 37 coming off the spool (not shown) enters the rear end of the yarn-guide tube 39; an obtuse angle being formed between the generally vertical path of the thread before entry into the yarn-guide tube 39 and the inclined path of the yarn inside the tube 39.

The thread or yarn 37 emerges from the forward end of the yarn-guide tube 39 and enters the rear end of the yarn-guide tube 38 as shown particularly in Figures 1 and 9; its path being further inclined thereby. The thread or yarn emerges from the forward end of the yarn-guide tube 38 generally parallel to the yarn-guide finger 21, and passes along said finger 21 and within the groove of the tongue 34 over the bend zone 33 and passes through the delivery or pay-out tube 36 from which it is paid out across the needle bank (not shown) in conventional manner.

Due to the angle made by the thread or yarn 37 in entering the rearmost yarn-guide tube 39, an appreciable amount of wear results at the rear end of said tube 39.

Accordingly, it is necessary from time to time to replace the yarn-guide tube 39. This can be done quickly and easily by simply gripping the rearmost end of said tube 39 with any suitable

gripping tool and pulling it out from between the grooved bridging portions. A new yarn-guide tube can then be inserted as described hereinabove by simply passing it between bridging strips 42 and 43 from the rear end of the base plate 20.

The yarn-guide tube 38 receives considerably less wear than the rear tube 39 and, therefore, has a much longer life. If and when it becomes necessary to replace the tube 38, this can be done by gripping the forward end of said tube and pulling it out from between the bridging strips 48 and 49. A new yarn-guide tube can then be inserted from the front end of the yoke-plate 28.

In Figures 2 and 11, I have shown a modified form of the present invention in which the yoke-plate 28 of Figure 1 is omitted and, instead, the bolts 32 are provided with washers 50 to hold the finger 21 to the slotted forward end of the base plate 20—a.

The yarn-guide tube 38 (instead of being supported intermediate the bridging strips of the yoke-plate as in Figure 1) is removably positioned intermediate bridging strips 42—a and 43—a formed intermediate the slots 27 of the forward portion 25—a of the base plate 20—a; the bridging strips 42—a and 43—a being generally similar to the bridging strips 42 and 43 holding the rear yarn-guide tube 39.

Still another embodiment of the present invention is shown in Figures 3 and 5.

The embodiment of Figures 3 and 5 generally resembles the embodiment of Figure 1 except that (in place of the bridging strips 42 and 43 and 48 and 49) a pair of juxtaposed ears 51 are struck out from the rearward portion 26—b of the base plate 20—b generally intermediate the bolts 23; the ears 51 extending upwardly from said portion 26—b so as to permit the insertion therebetween of the tube 39 as shown in Figure 5.

Similar ears 52 are struck out from the yoke-plate 28—b and extend upwardly therefrom; the ears 52 being adapted removably to receive and hold the yarn-guide tube 38.

It is evident that the rear yarn guide tube 39 changes the path of travel of the thread or yarn 37 from a generally vertical path as shown in Figures 1, 2 and 3 to a somewhat inclined path and that the front yarn guide tube 38 again changes the path of travel of the thread or yarn 37 to a further inclined path generally paralleling the yarn guide finger 21. Thus, the thread or yarn 37 is guided accurately and with a minimum of friction and wear along the path which it must travel in order to be fed to the needle bank.

In Figure 12 I have shown a modified form of rear yarn guide tube 39—a. The front portion of the yarn guide tube 39—a generally resembles the tube 39 described hereinabove. However, the rear end of the tube 39—a is bent upwardly as at 53 and has its uppermost tip flared as at 54. This modified form of rear yarn-guide tube is more efficient in changing the path of travel of the thread or yarn 37 and further reduces the friction and wear resulting from said change.

Where finer gauge thread or yarn must be used, the tubes 38, 39 and 39—a can be given smaller inside diameters by simply increasing the wall thickness thereof; the outside diameters being maintained the same so that all tubes are interchangeable and can fit within the bridging strips or ears of the base plate and/or yoke plate.

The present invention also contemplates the provision of two or more spaced pairs of ears 51 (instead of the single pair of ears 51 shown

in Figure 3) in order more firmly to hold the rear yarn guide tube 39.

The present invention also contemplates further modification of the embodiment of Figure 5 by replacing front and rear groups of bridging strips 42 and 43 by pairs of opposed ears 51 (for holding the tube 39), and by replacing the bridging strips 42—a and 43—a by one or more pairs of similar opposed ears for holding the tube 38.

The present invention may be embodied in other specific forms without departing from the spirit or essential attributes thereof, and it is therefore desired that the present embodiments be considered in all respects as illustrative and not restrictive, reference being had to the appended claims rather than to the foregoing description to indicate the scope of the invention.

Having thus described the invention, what I hereby claim as new and desired to be secured by Letters Patent is:

1. A yarn carrier including a finger, a base having a generally plane rear portion and a generally plane front portion tilted relative to said rear portion, means formed integrally with said rear portion for removably mounting a thin elongated quick attachable and detachable replaceable yarn guide tube generally parallel to said rear portion, and means for removably mounting a second thin elongated quick attachable and detachable replaceable yarn guide tube generally parallel to said front portion, said first-mentioned tube being generally co-extensive with said rear portion and having its front end disposed generally in line with the bend-zone separating said front and rear portions.

2. A yarn carrier including a finger, a base having a generally plane rear portion and a generally plane front portion tilted relative to said rear portion, means formed integrally with said rear portion for removably mounting a thin elongated quick attachable and detachable replaceable yarn guide tube on said rear portion, and means formed integrally with said front portion for removably mounting a second thin elongated quick attachable and detachable replaceable yarn guide tube on said front portion, said first-mentioned tube being generally co-extensive with said rear portion and having its front end disposed generally in line with the bend-zone separating said front and rear portions.

3. A yarn carrier comprising a base, a yarn guide finger, means including a yoke-plate and a pair of transversely-spaced bolts for adjustably connecting said finger to the front end of said base, and means formed integrally with said yoke-plate for removably holding a thin elongated quick attachable and detachable replaceable yarn guide tube generally parallel to the front end of said base, said holding means comprising a plurality of spaced transversely-extending bridging strips adapted to overlie said tube.

4. A yarn carrier comprising a base, a yarn guide finger, means including a yoke-plate for adjustably connecting said finger to the front end of said base, means for removably mounting a yarn guide tube at the rear end of said base, and means for removably mounting a thin elongated quick attachable and detachable yarn guide tube upon said yoke plate, said mounting means including a plurality of spaced transversely-extending bridging strips formed on said base and passing above said tube.

5. A yarn carrier including a base, a replaceable yarn guide tube adapted to be mounted at said base, and means comprising a plurality of spaced

transversely-extending bridging strips formed integrally with said base for removably holding said yarn guide tube.

6. A yarn carrier including a base, a replaceable yarn guide tube adapted to be mounted at said base, and means comprising a plurality of transversely-extending bridging strips adapted removably to hold said yarn guide tube, said bridging strips passing alternately above and below said tube.

7. A yarn carrier comprising a base, a yarn guide finger, means including a yoke-plate for adjustably connecting said finger to the front end of said base, and means for removably mounting a replaceable yarn guide tube upon said yoke-plate, said means comprising a plurality of integrally formed bridging strips passing alternately above and below said tube.

8. A yarn carrier comprising a base, a yarn guide finger, means including a yoke-plate and a pair of transversely-spaced bolts for adjustably connecting said finger to the front end of said base, and means for removably mounting a thin elongated quick attachable and detachable replaceable yarn guide tube upon said yoke-plate, said means comprising a pair of opposed ears struck out of said yoke-plate and extending upwardly therefrom and adapted to hold said tube

therebetween, said ears being disposed generally in transverse alignment with said bolts.

ERNEST A. FEUSTEL.
